Letters Patent No. 2361. Dated July 17. 1866.

Design for a Stove.

The Schedule referred to in these Letters Patent, and making part of the same.

To all whom it may concern:

Be it known that we John Martino, Jacob Beesley & John Currie of the City of Philadelphia, in the County of Philadelphia, in the State of Pennsylvania, have invented and originated a new Design for Stoves of which the following is a full, clear and exact description, reference being had to the accompanying drawing (Photographs) making part of this Specification.

Figure 1. is a view of the right hand side of our Stove.

Figure 2. is a view of the left hand side of Do.

Fig. 3. is a front view of the upper front of our Stove.

Fig. 4. is a front view of the lower front of our Stove.

What we claim as our invention, and desire to secure by Letters Patent of the United States is

The Design for "Stoves," as herein set forth and shown:

Witnessed,

Lionel J. D. Epineuil.
